ATTORNEY

UNITED STATES PATENT OFFICE.

WILLIAM E. HART, OF NEAR SAN JOSE, CALIFORNIA.

VACUUM FUEL-FEED TANK.

Application filed May 15, 1923. Serial No. 639,143.

To all whom it may concern:

Be it known that I, WILLIAM E. HART, a citizen of the United States, and residing near San Jose, in the county of Santa Clara and State of California, have invented certain new and useful Improvements in Vacuum Fuel-Feed Tanks, of which the following is a specification.

It is one object of this invention to provide an improved form of vacuum fuel feed tank wherein the telescoping chamber construction common to such devices is eliminated.

It is another object of my invention to provide a structure of the character indicated that has the fuel intake and discharge, and also the suction pipe whereby the fuel is drawn into the tank connected to the lower end thereof.

It is a further object of my invention to provide a device of the character indicated wherein the several chambers and conduits are, with the exception of the short connections to the valves, formed in one integral whole.

Finally, it is an object of the invention to provide a device of the character indicated that will be simple in form, economical to manufacture, quickly and easily assembled and disassembled, and highly efficient in its practical application.

In the drawing:—

Figure 1 is a side elevation of my invention.

Figure 2 is a top plan view of the same.

Figure 3 is a bottom plan view of the same.

Figure 4 is a sectional view on line 4—4 of Figure 2.

Figure 5 is a section on line 5—5 of Figure 2, parts being broken away.

Figure 6 is a section on 6—6 of Figure 2, partly broken away.

Figure 7 is a sectional view on line 7—7 of Figure 1.

Referring more particularly to the drawing, 1 indicates a sheet metal tank of suitable dimensions having its four corners partitioned off as at 2 to form conduits 3, 4, 5 and 6, these conduits being closed at their upper ends, but conduits 3, 4 and 6 being fitted with short tubes 7, 8 and 9 respectively. The lower end of conduit 3 is closed off from the interior of the tank but is provided with an opening 10 by means of which connection may be made to the manifold of

an internal combustion engine, not shown, and desired suction created in conduit 3. Conduit 4 communicates with the interior of the tank at its lower end and a pipe 11 is fitted into the bottom of the tank 1 and extends upwardly a distance into conduit 4 as shown, this pipe providing an outlet from the tank through which fuel is conducted to the carburetor not shown. Conduit 6 is also closed off from the interior of the tank but is provided with a passage 12 by means of which fuel is admitted thereto from a supply tank not shown.

The interior of tank 1 is also divided into two chambers as 13 and 14, the latter being the float chamber and communicating with chamber 13 by means of a tube 15 extending downwardly to a point near the bottom of chamber 13. In the bottom of chamber 13 is arranged an opening 16 fitted with a plug 17 carrying a bow 18 having an orifice 19 therein. Loosely arranged in orifice 19 is a pin 20 carrying a disc 21 and flattened out and twisted as at 22 to form a vane insertible in tube 15.

The chamber 14 is fitted with a float 23 having a stem 24 engaging tube 15 and pivoted to a lever 25. Lever 25 is pivoted to a support 26 on cover 38 at one end and to an arm 27 at the other end, the arm 27 extending upwardly and being pivotally connected to a second arm 28. Arm 28 is pivotally connected to a valve operating arm 29 pivotally mounted on hangers 30 intermediate its ends, and a spring 31 connects the outer end of arm 29 with the upper end of arm 27. Lever 25 is provided with shoulders 32 to limit its movement in either direction, and valve stems 33, 34 are connected to the outer end of arm 29 as shown. From the foregoing it may be clearly seen that the lowering of float 23 causes spring 31 to move downwardly past the pivotal connection between arms 28 and 29 whereupon, by virtue of its resiliency, it quickly snaps into the position shown in dotted lines at 35 thereby reversing the positions of valves 36, 37 on stems 33, 34 respectively.

At 38 is shown a cover secured on tank 1 by means of a bar 39 passing thereover and engaging slots 40 in bars 41 pivoted to opposite sides of tank 1 as at 42. When gasket 43 is in position the top may be secured tightly in position by tightening up set screw 43^a in bar 39 and engaging the top of cover 38.

Cover 38 has a conduit 44 formed therein closed at its outer end by a removable plug 45 and communicating at its inner end with tube 7, when the cover is on tank 1, and 5 through tube 7 with conduit 3. This conduit 44 is provided with a valve seat 46 to receive valve 36.

At 47 is a second conduit in cover 38 closed at its outer end by a removable plug 10 48 and communicating at its inner end with conduit 4 in tank 1 through tube 8. This conduit is provided with a valve seat 49 directed oppositely to valve seat 46 and receiving valve 37. An air vent valve is shown 15 at 50 removably inserted in cover 38 to communicate with conduit 47 and fitted with a cork valve 51 normally resting on a pin 52 but under pressure from within movable outwardly to close passage 53 in said valve.

20 At 54 I provide another conduit in cover 38 provided with a removable plug in its outer end and at its inner end communicating with conduit 6 through tube 9 when the cover is in position. This conduit also 25 communicates with chamber 14 in tank 1 at 55 and is fitted with a screen 56.

It is here briefly pointed out that the part 21, 22 is the only movable part mounted on tank 1. The float and its operating mechanism and the valve structure just described are all mounted on the cover 38 and are removed from the tank when the cover is removed and are, therefore, readily accessible.

30 35 The operation of the device, it being assumed that it is properly connected to a supply tank, a carburetor, and the manifold of an engine, the valves being in the position shown, is as follows.

40 45 The suction from the manifold draws air out of chamber 14 through valve 36, 46, conduit 44, tube 7, conduit 3 and passage 10. The exhaustion of air from chamber 14 draws liquid fuel into the same through conduit 54, tube 9, conduit 6 and passage 12. As the liquid drawn into chamber 14 rises it raises the float 23 until the valve operating mechanism is operated as heretofore described, whereupon the valve 36 is closed 50 and valve 37 opened. This action shuts off the suction from the engine and opens the chamber to atmospheric pressure. While the arrangement of valve 51 permits air to enter at all times yet if undue tipping of the tank causes liquid to flow out through tube 8 it will close the port 53 and prevent loss of fuel. As the float falls on account of use of fuel it will of course reverse the positions of the valves and permit a new 55 supply of fuel to be drawn into the chamber 14.

60 The tubular passage 11 extends to a height above the bottom of tube 15 in order to keep the end thereof wet and obviate the necessity of priming. The chamber 13, is, of course,

ordinarily kept full of liquid from chamber 14 through tube 15. It is necessary to quickly and accurately close tube 15 when fuel is being drawn into chamber 14, and this is accomplished by the disc 21 seating against the lower end of tube 15, its action being quickened and rendered accurate by its being revolved through the action of the liquid on the twisted part 22.

70 75 It may now be seen that I have provided a device wherein all of the exterior connections are made at the bottom thereof, thereby permitting placing the device higher up than is possible with the usual form of construction and permitting the removal of 80 the cover by simply loosening the clamp and without disturbing any of the connections to the device.

85 It is to be understood, of course, that while I have herein shown and described one specific embodiment of my invention, changes in form, proportions, construction and method of operation may be made within the scope of the appended claims.

90 I claim:

1. A tank of the character indicated comprising a shell having at least three corners partitioned off to form conduits, tubular elements arranged in the upper ends of said three conduits, one of said three conduits having communication with the interior of said shell at its lower end and having a discharge passage arranged therein, and the other two of the said three conduits being closed off from the interior of the shell but communicating with the exterior thereof at their lower ends, and a partition arranged in the shell to divide the same into upper and lower chambers, and a conduit connecting said chambers. 100

105 2. A tank of the character indicated, comprising a shell having conduits arranged therein and extending longitudinally thereof, one of said conduits having communication with the interior of said shell at its lower end and having a discharge passage arranged therein, and the second and third of said conduits being closed off from the interior of said shell but communicating with the exterior thereof at their lower ends, a partition arranged in the shell to divide the same into an upper and a lower chamber, a conduit depending from said partition and communicating with said chambers, and a liquid pressure operated valve mounted in 110 115 said last mentioned conduit.

120 3. A tank of the character indicated, comprising a shell having conduits arranged therein and extending longitudinally thereof, one of said conduits having communication with the interior of said first shell at its lower end and having a discharge passage arranged therein, and the second and third of said conduits being closed off from the interior of said shell but communicating 125 130

with the exterior thereof at their lower ends, a partition arranged in the shell to form upper and a lower chamber, a conduit depending from said partition and communicating 5 with said chambers, a cover for said shell, a float and float operated mechanism including a pair of oppositely acting valves mounted on said cover and insertable in said upper chamber, and conduits controlled by 10 said valves arranged in said cover.

4. A tank of the character indicated, comprising a shell having conduits arranged therein longitudinally thereof, a partition arranged therein to form an upper and a 15 lower chamber, a conduit depending from said partition and communicating with said chambers, one of said conduits communicat-

ing with said lower chamber and having a fuel discharge arranged in the lower end thereof and communicating with the upper 20 chamber at its upper end, a second conduit having a fuel inlet arranged at its lower end and a discharge into the upper chamber arranged at its upper end, a third conduit provided with an outlet at its lower end and 25 communicating with the upper chamber at its upper end, oppositely acting valves arranged to control communication between said first and third conduits and said upper chamber, and float operated mechanism for 30 simultaneously operating said valves in opposite directions.

WILLIAM E. HART.
